UNITED STATES PATENT OFFICE

FRANCIS J. CANTIANICH, OF NEWPORT NEWS, VIRGINIA

SAFETY APPLIANCE FOR GAS BURNERS

Application filed December 9, 1929. Serial No. 412,885.

My invention relates to devices for preventing the escape of gas from illuminating and other burners when the gas is not ignited, or having been ignited, when the flame has been put out by accidental means, as by being blown out. Many lives have been lost and much property damage has occurred due to the careless use of gas burners and the accidental extinguishing of the flame by drafts of air or temporary failure of gas flow, etc.

My invention, therefore, has for its object to provide means whereby accidents due to gas escape may positively be avoided.

Further, the invention has for an object to provide means for shutting off the gas at the burner in the event that the gas pressure in the mains fails for any reason, as a break in the mains for example.

Further, it is an object of the invention to provide a gas burner with safety devices whose action depends upon the presence and absence of heat generated by ignited gas issuing from an orifice of the burner, which devices will, under any and all conditions met with in practice, serve to cut off the gas from the outlet of the burner at all times save when the gas at the burner opening is burning.

Further, it is an object of the invention to provide a gas burner with an automatic shut-off valve of such construction that it will not stick, its ports will not clog, and it will maintain a gas-tight contact with its seat at all times, automatically taking up wear which may occur between engaging surfaces and without the necessity of using pressure springs.

Further, it is an object of the invention to provide a device of the above character which has means for protecting itself against failure in the event of the breakage or burning off of the tip of the thermostat control element.

Again, it is an object to provide a device of the character above indicated wherein provision is made to prevent clogging the gas duct to the valve seat port, the valve port, and the duct from the valve seat port to the burner outlet, by the provision of a fine mesh screen located at the entrance to the burner

which will filter out or prevent passage of dust particles or particles of other foreign matter before the gas passes into the gas duct.

A further object is to provide a burner of the character stated in which the contacting faces of the valve and the valve seat lie in vertical planes and in which gravity acts to hold these faces in gas-tight contact at all times, while permitting free and easy sliding of the valve to bring its ports into and out of register with those of the valve seat that are associated with the gas inlet and outlet ducts.

Further, it is an object to provide a device of the character specified above, which is simple in its construction, is composed of but few parts, is inexpensive to manufacture, and thoroughly practical in its make-up and operation.

Further, it is an object to provide a burner embodying the aforesaid advantageous features which may be said to be "fool-proof" in that it may be operated by anyone without the risk of putting the burner out of operation, and in that if the tip of the thermostat element, which is exposed to the heat of the flame, burns off after a time, it will not prevent the automatic operation of the device for the purpose of closing the valve and shutting off the gas flow promptly.

Other objects will in part be obvious and in part be pointed out hereinafter.

To the attainment of the aforesaid objects and ends, my invention consists in the novel features of construction and in the combination, connection and arrangement of parts, hereinafter more fully described, and then pointed out in the appended claims.

In the drawings:

Figure 1 is a perspective view illustrating the preferred embodiment of the invention in use.

Figure 2 is an enlarged elevation of the invention, the case of the burner being shown in vertical section and the parts being in the position they assume when the valve is closed.

Figure 3 is a view similar to Figure 2 with the parts in the position they assume when the valve is open.

Figure 4 is a view similar to Figure 3 after

the thermostat element's tip has been broken or burnt off, the safety blade and stirrup being released and the spring finger functioning to hold the valve closed.

5 Figures 5 and 6 are side elevations of the invention taken at opposite sides of Fig. 2 with the parts in the position shown in Figure 2.

10 Figure 7 is a vertical longitudinal section on the line 7—7 of Figure 2, looking in the direction of the arrow.

15 Figure 8 is a detail perspective view of the valve.

Figure 9 is a detail perspective view of the 15 valve moving lever.

Figure 10 is a detail perspective view of the stirrup member and safety blade.

Figure 11 is a detail perspective view of the deformable thermostat element.

20 In the drawings, in which like numerals of reference indicate like parts in all of the figures, and which drawings illustrate the preferred embodiment of my invention, it will be noted that the burner is composed of a 25 pillar having a lower flange 1 and an upper flange 4, between which is located the valve mechanism.

Beneath the lower flange 1 is an internally 30 threaded socket 2 by means of which the burner can be screwed onto the fixture pipe as indicated in Figure 1. Within the socket 2 is located a fine mesh wire screen 3, the purpose of which is to filter out, or hold back, dust and other foreign matter particles in the 35 gas stream so that pure gas only is delivered to the duct 9 which conveys the gas from the screen to the lower port 8 of the valve seat.

5 designates a cylindrical portion of the pillar, located just beneath the flange 4, and 40 between the cylindrical portion 5 of the pillar and the lower flange 1, the pillar is flattened to provide a flat wall 6 having transverse slots 7 through which the arms 20 of the valve 18 project.

45 10 designates the upper port of the valve seat, which communicates through the upper duct 11, with the tip holder socket 12 in which the tip 13 (constructed of the usual material such as lava or other high temperature resisting substances) is located. The tip 13 has its slot 14 so positioned that the flame of the burner will lie in a plane transversely of that containing the flat wall 6.

The upper flange 4 has a slot 15 and a recess 55 16 which leaves a projection 17, the purpose of which will presently be explained.

The valve, which constitutes an essential part of my invention, is composed of a body 18 and arms 20 having inclined fingers 21, 60 the arms projecting through the slots 7 and the fingers 21 lying on the slot edge of the wall 6 opposite the valve seat face of the wall. As will be seen by reference to Figure 5, the arms 20 do not lie on the wall 6 within 65 the slot but the weight of the valve is sus-

tained by the fingers 21 in engagement with the edge of the wall at the slot and by the contact of the working face of the valve with the valve seat face of the wall 6. Thus the weight of the valve 18 is utilized through the 73 inclined fingers 21 and edges of the wall at the slots 7 to maintain a gas-tight contact between the opposing faces of the valve 18 and the wall 6 while leaving the valve free to be slid transversely in the direction of the slot 7 to bring the port 19 of the valve 18 into register with the ports 8 and 10 or out of register with the same as the case may be. 75

The wall 6 of the pillar of the burner is provided with a bearing hole 22 for the reception of the stub shaft 23 of the rocking lever. This rocking lever is composed of a finger 25 to engage one side wall of the valve 18 and an arm 24 to which a pull chain 45 is connected. The rocking lever also includes 80 a plate 26 between which and the wall 6 the valve 18 lies. The plate has an edge 27 to cooperate with the flange 1 as a stop when the valve is in the closed position. The finger 25 serves to push the valve 18 to the closed 85 position when the rocking lever is rocked from the position shown in Figure 3 to the position shown in Figure 2.

A pin 28 is carried by the plate 26 to fit 90 into the stirrup 29 of the thermostat device.

The stirrup 29 is provided with an arm 30 having a finger 31 to engage the side of the valve 18 opposite to that engaged by the finger 25 so that by rocking the rocking lever, through the medium of the pull chain, the 95 valve may be moved from the closed to the open position and by rocking the valve by means of the thermostat device it may be moved from the open to the closed position. The stirrup 29 is carried by a blade 32 which 100 is apertured at 33 to receive a rivet that connects the blade to the distortable element of the thermostat, the latter having a rivet hole 38 to receive the rivet 39 that holds the parts together.

A blade 35, which I term a safety blade, is 105 also provided and is connected to the blade 32 by a connection 34. If desired the blades 32 and 35, the connection 34 and the stirrup 29 may be stamped from a single piece of 110 sheet metal.

The safety blade 35 is provided with a hook 36, the purpose of which is to retain the free end 44 of a coil spring 43 whose other end 42 is mounted in a block 41 that is secured 115 to the holding clip 40, which clip retains the element 37 in position on the projection 17 hereinbefore referred to so as to locate the upper or tip end of the thermostat element within the heat range or zone of the burner 120 flame.

125 It should be, of course, understood that the element 37 is flat and composed of two co-extensive leaves integrally secured together, and of metals having different coeffi- 130

clients of expansion, such as German silver and steel as is well known in the art of thermostats.

Held over the parts hereinbefore described is a shell or casing 46 which has a slot 47 through which the chain carrying arm 24 projects and another slot 48 through which the thermostat device projects. This casing 46 is preferably permanently sealed to the flange 1 so that unauthorized access to the interior parts is prevented, though if desired the casing 46 may simply be held in place by retaining friction or by the use of a fastening screw.

In practice the normal position of the parts is disclosed in Figure 2. Now when it is desired to use the burner one pulls the chain 45 which causes the valve 18 to be moved from the position shown in Figure 2 to the position shown in Figure 3. Gas then passes through the ducts 9 and 11 via ports 8, 19 and 10 to the tip 13 where it issues through the slit 14 and may be ignited in the usual way. It should, of course, be understood that the chain should be held down to keep the valve in the open position for a few seconds until the thermostat element has been warmed sufficiently to cause it to buckle and thus hold the valve in the open position. Now, should, for any reason, the gas supply fail which would put out the light, or should the light be blown out accidentally while gas is flowing, the thermostat element will cool and consequently return to its normal position, thereby moving the valve from the position shown in Figure 3 back to the position shown in Figure 2 and shutting off the flow of gas.

In the event that the tip of the thermostat device burns off or the thermostat device becomes broken, the stirrup 29 and the safety blade 35 will fall by gravity assisted by the action of the spring 43 and the end 44 of the spring 43 will engage the pin 28 and move the valve 18 from the open position shown in Figure 3 to the closed position shown in Figure 4, thus shutting off the flow of gas to the burner tip.

From the foregoing it will be seen that with the construction embodied in my invention the cost of manufacture is kept down to the minimum. The valve 18 and its arms and fingers 20, 21 may be cast as may also the burner pillar and the rocking lever. The stirrup and other parts of the thermostat device can be stamped from sheet metal. The work of assembling the parts is very simple and they can be assembled rapidly and without the use of particularly skilled labor.

Not only is the device so constructed as to function under all conditions met with in practice but it has been an object to provide such a device that is of neat appearance and of compact structure.

From the foregoing description, taken in connection with the accompanying drawing,

it is thought the construction, operation and advantages of my invention will be clear to those skilled in the art.

What I claim is:

1. In gas burners, a pillar having a tip holder and a member for mounting the burner on a gas supply fixture, said pillar having a vertically disposed flat face with gas ports and ducts leading from said ports to the supply fixture and to the tip holder respectively, a slide valve having a flat face to engage said vertically disposed flat face and having a port to control gas passage between said gas ports; gravity actuated means to hold said valve in gas-tight contact with said flat face; a thermostat device associated with the valve for holding said valve in the open position when the gas issuing from the burner is ignited and to move said valve to and hold it in the closed position when the flame is extinguished, and manually operated means to move the valve to the open position initially.

2. In gas burners, a pillar having a tip holder and a member for mounting the burner on a gas supply fixture, said pillar having a vertically disposed flat face with gas ports and ducts leading from said ports to the supply fixture and to the tip holder respectively; a slide valve having a flat face to engage said vertically disposed flat face and having a port to control gas passage between said gas ports; gravity actuated means to hold said valve in gas-tight contact with said flat face; a thermostat device associated with the valve for holding said valve in the open position when the gas issuing from the burner is ignited and to move said valve to and hold it in the closed position when the flame is extinguished, and manually operated means to move the valve to the open position initially, and another means operating to cause said valve to be moved to the closed position should said thermostat device become broken or disconnected.

3. In gas burners, the combination with a burner having a gas passage, a valve controlling said passage, a thermostat device to hold said valve with its passage in the open position when the gas issuing from the burner is ignited and to operate said valve to close said passage when the gas issuing from the burner is extinguished; of a safety device distinct from the thermostat device to hold said valve in a position to close said passage in the event of breakage or burning off of said thermostat device in a manner to render it inoperative.

4. In a gas burner wherein is provided a body having an entrance aperture and an exit aperture and having valve controlled ducts between said entrance and exit apertures, said body including a valve seat face with ports that terminate at the adjacent ends of said ducts; a valve body having

a connecting port and being freely slidable over said valve seat face; means to hold said valve continuously in gas-tight contact with said valve seat face; an element having 5 a part to engage one side of said valve for pushing it one way; a thermostat device having a part to engage the other side of said valve for pushing it the other way, and a connection between said element and said thermostat device to cause same to move in unison, 10 and means by which said element may be caused to move said valve to an open position and hold it there while said thermostat device is warming up.

5. In a gas burner wherein is provided a body having an entrance aperture and an exit aperture and having valve controlled ducts between said entrance and exit apertures, said body including a valve seat face with 15 ports that terminate at the adjacent ends of said ducts; a valve body having a connecting port and being freely slidable over said valve seat face; gravity actuated means to hold said valve continuously in gas-tight contact with said valve seat face; an element having 20 a part to engage one side of said valve for pushing it one way; a thermostat device having a part to engage the other side of said valve for pushing it the other way, and a connection between said element and said thermostat device to cause same to move in 25 unison.

6. In a gas burner wherein is provided a body having an entrance aperture and an 30 exit aperture and having valve controlled ducts between said entrance and exit apertures, said body including a valve seat face with ports that terminate at the adjacent ends of said ducts; a valve body having a connecting port and being freely slidable over said 35 valve seat face; means to hold said valve continuously in gas-tight contact with said valve seat face; an element having a part to engage one side of said valve for pushing it one way; a thermostat device having a part to engage 40 the other side of said valve for pushing it the other way, and a releasable connection between said element and said thermostat device to cause same to move in unison.

5. In a gas burner wherein is provided a body having an entrance aperture and an exit aperture and having valve controlled ducts between said entrance and exit apertures, said body including a valve seat face with 55 ports that terminate at the adjacent ends of said ducts; a valve body having a connecting port and being freely slidable over said valve seat face; means to hold said valve continuously in gas-tight contact with said valve seat face; an element having a part to engage one side of said valve for pushing it one way; a thermostat device having a part to engage the other side of said valve for pushing it the other way, and a connection between said 60 element and said thermostat device to cause

same to move in unison, and a safety device associated with said thermostat device and with said element for causing the movement of said valve to a closed position in the event said thermostat device is rendered inoperative. 70

8. A burner having a body with a gas inlet and a gas outlet and a ported passage between the same; a vertically positioned slide valve located on said body with a port to open and close the ports of said ported passage, said body and valve having opposing contacting surfaces located in vertical planes wherein said ports are located; means whereby said surfaces are held in gas-tight contact while said valve is permitted to slide transversely for opening and closing said ports; and a thermostat device to hold said valve in the open position when said device is hot and to move said valve to and hold it in the closed position when said device is cold, and means for effecting movement of said valve to its open position initially. 75

9. A burner having a body with a gas inlet and a gas outlet and a ported passage between the same; a vertically positioned slide valve located on said body with a port to open and close the ports of said ported passage, said body and valve having opposing contacting surfaces located in vertical planes wherein said ports are located; means whereby said surfaces are held in gas-tight contact while said valve is permitted to slide transversely for opening and closing said ports; and a thermostat device to hold said valve in the open position when said device is hot and to move said valve to and hold it in the closed position when said device is cold, means for effecting movement of said valve to its open position initially, and means independent of the heat of the flame for moving said valve to a closed position should said thermostat become broken or burnt off so as to render it inoperative. 80

10. In gas burners having a body with a vertical wall which has a flat valve seat face, and intake and outlet ports therein; a ported slide valve having a flat face to engage said seat; means to hang said valve on said body with provisions enabling gravity to hold said flat faces in gas-tight contact; and means to move said valve parallel to said flat faces to open and close said ports. 85

11. In gas burners having a body with a vertical wall which has a flat valve seat face, and intake and outlet ports therein; a ported slide valve having a flat face to engage said seat; means to hang said valve on said body with provisions enabling gravity to hold said flat faces in gas-tight contact; and means to move said valve parallel to said flat faces to open and close said ports, said means including a rocking lever and a thermostat device associated therewith for rocking the same. 90

12. In gas burners having a body with a vertical wall which has a flat valve seat face, and intake and outlet ports therein; a ported slide valve having a flat face to engage said seat; means to hang said valve on said body with provisions enabling gravity to hold said flat faces in gas-tight contact; means to move said valve parallel to said flat faces to open and close said ports, said means including a rocking lever and a thermostat device associated therewith for rocking the same, and a safety device associated with said lever and thermostat device to cause said lever to move said valve to the closed position at times substantially as specified.
